UNITED STATES PATENT OFFICE

JAMES W. KENT, OF BROOKLYN, NEW YORK

ROLLER MILL

Application filed May 9, 1929. Serial No. 361,636.

This invention relates to roller mills of the type adapted for grinding paints, inks, chocolate and like substances and materials. The object of the invention is to provide a roller mill for these purposes embodying certain novel features whereby to increase the efficiency of the machine and improve its construction.

One object of the invention is to provide improved means for adjusting the rollers and to regulate the pressures between them. Another object is to provide a five roller mill in which the rollers are arranged in a novel manner. Still another object is to provide means for feeding the material from a hopper by a small take off roller. Other objects of the invention are to provide an improved delivery apron and visible means for indicating the pressure between the different rollers.

Still other objects and features of the invention will appear from the following specification read in connection with the accompanying drawings in which

Figure 1 is an end view of a roller mill embodying the invention, parts being omitted and other parts being broken away.

Figure 2 is a front view of the mill with parts omitted and broken away.

Figure 3 is a rear view of the machine with parts omitted.

Figure 4 is a diagrammatic view of the gearing.

In the drawings the reference numeral 5 denotes a hollow housing or framework in which there is mounted a plurality of grinding rollers 6, 7, 8, 9 and 10. The roller 6 is also a feed roller.

The other main grinding rollers are provided with shafts 11, 12, 13 and 14 journaled in slidably supported bearing boxes 15, 16, 17 and 18. It will be understood that the construction and arrangement of these parts as shown in Figure 1 are duplicated at the other side of the machine.

The roller bearing boxes are kept in place by top bars or braces 19, 19 and front bars or braces 20, 20. The rolls are kept in frictional grinding contact with each other and are adjustable so as to regulate the pressure between them. The adjustment, however, is regu-

lated with reference to the third roller 8 the bearings 16 of which are clamped in position between the frame and the front bars 20.

The second roll 7 is adjusted with reference to the roll 8 by the following means. The reference numeral 22 denotes spacing blocks which are clamped between the front bars 20 and the frame 5 leaving room for the bearings 15 to slide in. Springs 23 are interposed between the bearings and the frame.

In front of the roller 15 and at each end there is mounted on the frame a bracket 24 which supports a shaft 25 which engages the bearing 15. The shaft carries a gear 26 in mesh with a pinion 27 on an adjusting shaft 28 which extends parallel with the roll 7. By rotating the shaft 28 the bearings 15 will be adjusted with relation to the third roll 8, the springs 23 providing the necessary yielding resistance to the movement of the bearings 15 in a well known manner.

In order to compensate for wear or unevenness in the roll 7 and its bearings there is provided a micrometer adjustment at one end thereof comprising a sleeve 30 slidably carried in the block 22.

The shaft 25 is threaded through the sleeve, and the latter is finely adjusted in relation to the block by a bolt 31 which is screwed into the block and passes through an extension or head 32 of the sleeve 30.

It will therefore be seen that by turning the bolt 31, the sleeve, which serves as a nut for the shaft 25, will be adjusted with relation to the bearing 15, hence take up for wear at the one end of the roll 7 so as to keep the latter in true parallelism to the third roller 8. The micrometer adjustment is therefore required at only one end of the rolls as is obvious.

In front of the bracket is mounted a casing 34 which encloses a gear 35 fast on the shaft 25 and in mesh with a wide pinion 36 which operates a pointer 37 over a scale 38. The parts are so arranged that as the pressure of the roll 7 against the roll 8 is adjusted, the pointer 37 will be rotated and indicate the pressure on the scale in a well known manner.

The pressure indicating means are located at only one end of the roller as seen in Figure 100

2. The gear 35 slides on the pinion 36 as the pressure is adjusted.

The means for adjusting the roll 7 are duplicated above the roll 9 for adjusting the latter also with relation to the roll 8 and the 5 parts are similarly numbered. Springs 39 are interposed between rolls to provide yielding frictional contact between rolls 8 and 9. The bearings 17 slide vertically between the front bars 20 and spacing blocks 40 clamped 10 to the frame by the top bars 19.

Again, as seen in Figure 3, the fifth roll 10 is adjusted towards the roll 9 by still a third unit of adjusting mechanism similar to the one described above and similarly numbered. In this case springs 42 are interposed between the blocks 40 and the bearings 18. The shafts 25 for adjusting the roll 10 pass through spacing blocks 43. In all three cases referred to the pressure indicating means are 15 also provided as shown. The operating shafts 20 also carry suitable handwheels 44.

From the foregoing it will be seen that the pressure between adjacent rolls is adjustable 20 separately and may be observed by the indicating means for each adjustable unit.

To the bearing boxes 15 at each end of the roll 7 there is bolted a bracket 50, see Figures 1 and 2. The brackets occupy the spaces between the ends of the roller 7 and the front bars 20, the boxes being wide enough to have the brackets bolted thereto as will be understood.

The brackets 50 extend upward and support in slidable relation smaller bearing boxes 51 in which the feed roll 6 is journaled. The feed roll may be adjusted with relation to the roll 7 by screws 52. The brackets 50 support between them the feed hopper 54 which 35 contains the material to be ground. The feed hopper is provided with lugs 55 through which pass screws 56. The latter are screwed into the brackets 50.

By this means, not only is the hopper supported, but it may be adjusted vertically with relation to the rolls 6 and 7. The bottom of the hopper is of course open and the sides 57 of the hopper are cut or shaped at the bottom as shown in Figure 1 at 58 to fit the contours 40 of the two rollers 6 and 7. These two rollers therefore form the bottom of the hopper.

The brackets 50 have slots 59 curved on an arc with the shaft 60 of the roll 6 as center. Bolts 61 pass through the slots and into bosses 62 in the sides of the hopper. When it is desired to clean the rolls or for other purposes, the screws 56 are loosened and the hopper swung outward until the bolts 61 reach the outer ends of the slots 59. The bolts 61 are 55 then tightened and maintain the hopper in outward tilted position, the sides of the hopper sliding with their bottom edges on the roll 6 as will be understood. The reverse movement puts the hopper back into position.

60 The material in the hopper is carried away

65 by the roll 6 and around the other rollers in the order named. From the last or fifth roller 10 the material is taken or scraped as it were by a blade 65 which is carried by a bar 66 parallel to the roll 10. The bar 66 is hinged at each end on a pin or stud 67 which is fast 70 in the adjacent bearing box 18.

75 The bearing boxes 18 have rearwardly and inwardly extending portions or wings 68. The lower parts thereof carry the pins 67. The upper parts have lugs 69 through which pass screws 70 which bear against the scraper bar 66 to one side of the pins 67. Hence, when the screws 70 are adjusted, the scraper blade 65 is tilted with respect to the roll 10.

80 The numeral 72 denotes a support secured to the frame and having a hole 73. A delivery chute or apron 74 extends downward from the scraper. The apron has a pin 75 which fits into the said hole 73 to support the lower part of the apron. The latter is formed with upstanding sides 76, the upper ends of which rest on the bar 66 at each end of the scraper blade as seen in Figure 3.

85 The delivery apron may therefore be detached very easily by a mere lifting movement to free it from the support 72. The scraper blade has sides 77 inside the delivery apron.

90 The rolls are driven as follows, see Figure 4. A driving shaft 80 extends through the frame and carries a pinion 81. The latter drives a gear 82 on roll shaft 13. Shaft 13 carries a pinion 83 which drives a gear 84 on the roll shaft 12 which also carries a pinion 85. The latter drives a gear 86 on roll shaft 11. On the other end of the machine shaft 11 carries a gear 87 which drives pinion 88 on roll shaft 60. The ratio of the gearing is such that each roll is driven at an increasing- 95 ly greater speed than the preceding roll.

100 Ink or other material which is to be ground is poured into the hopper 54 and the greater portion of the material will rest on the roll 7. A small portion of the ink will be carried away by the roller 7, but the greatest portion will be taken off by the slower moving feed roll 6 and deposited as a film on the roll 7 and then carried around from roll to roll and finally taken off the last roll 10 by the scraper 105 65. It will be seen that the construction provides for four points of grinding action between the five rolls so that when the process is completed a superfine ground material is obtained.

110 The means for adjusting the rolls contribute to a large degree to the superior grinding of the product, because each roll may be adjusted to a very fine degree with respect to the next roll by reason of the fact that the 115 adjustment, while being made with reference to obtain the proper grinding contact, nevertheless is made mechanically against the springs backed by a fixed member.

120 This has been found to be superior to 125

means of adjustment which operate merely between two rolls. In the latter case all inaccuracies or irregularities between the rolls are multiplied, whereas in the present instance, if one roll is inaccurately adjusted, 5 the fault is local for that particular roll. It has also been found to be of great advantage to provide the smaller feed roll 6 instead of a large feed roll which is slower in action. It is of course also an advantage 10 that the pressures between the rolls may at all times be accurately ascertained by looking at the gages 37—38.

In order to guard against undue spreading of the material, return guides 90 are provided for conducting surplus material from roll 9 down into the hopper 54. When the rolls are to be cleaned and the hopper is swung forward as described, a guard 91 protects the operator from having his hands 20 caught between the rolls 8 and 9. It is important to guard against accidents at this point because the operator reaches in over the hopper.

The pressure of the scraper 65 against the 25 last roller 10 may be accurately adjusted by the screws 70. The apron 74 is easily detached and the scraper bar and scraper removed by lifting the bar off the pins 67 thus giving easy access to the rear of the machine.

Rolling mills of the character described herein are usually provided with water cooling devices. These and other usual parts of the machine are not shown. It will further 30 be understood that changes may be made in the construction shown and described without departing from the essence of the invention and I therefore reserve the right to make such changes as fall within the scope of the 40 appended claims.

I claim:

1. A roller mill of the character described comprising in combination a first relatively 45 large grinding roll, a feed roll of materially less diameter mounted above and to one side of the said first roll, a pair of superposed grinding rolls mounted on the opposite side of the first grinding roll, a final grinding roll mounted on the same level as the uppermost of said pair of superposed grinding rolls, the said four grinding rolls being all of the same size, means for supporting each of said rolls in frictional grinding contact with the adjacent rolls and means for exerting pressure between each pair of adjacent rolls separate from the pressure on the other rolls.

2. A roller mill of the character described comprising in combination a first relatively 60 large grinding roll, a feed roll of materially less diameter mounted above and to one side of the said first roll, a pair of superposed grinding rolls mounted on the opposite side of the first grinding roll, a final grinding roll mounted on the same level as the upper-

most of said pair of superposed grinding rolls, the said four grinding rolls being all of the same size, means for supporting each of said rolls in frictional grinding contact with the adjacent rolls, means for exerting pressure between each pair of adjacent rolls 70 separate from the pressure on the other rolls and means for regulating and indicating said pressures.

3. A roller mill of the character described comprising in combination a first relatively 75 large grinding roll, a feed roll of materially less diameter mounted above and to one side of the said first roll, a hopper mounted above the said two rolls and having an open bottom through which a portion of the surfaces of said rolls project, the sides of said hopper having their lower edges curved to fit the contours of the rolls, means for adjusting the hopper with relation to the said two 80 rolls, other grinding rolls mounted on the other side of said first named grinding roll and means for maintaining all of said rolls in frictional grinding contact with each other.

4. A roller mill of the character described comprising in combination a first relatively 90 large grinding roll, slidably mounted bearing boxes for supporting said roll, brackets secured to said bearing boxes, smaller bearing boxes slidably supported in said brackets, a relatively smaller feed roller supported in said smaller bearing boxes and a hopper supported on the said bracket above the said two 95 rolls.

5. In a roller mill of the character described the combination of a plurality of individually adjustable grinding rolls, a feed roll of materially less diameter than any of the said grinding rolls, means for supporting said feed roll to move with one of said grinding rolls when the latter is adjusted, means for adjusting said feed roll individually with respect to the said one grinding roll and a hopper from which said feed roll is adapted to feed the material to the said one grinding roll.

6. In a roller mill of the character described the combination of bearing boxes, brackets secured thereto, a grinding roll mounted in said bearing boxes, a feed roll mounted in said brackets in contact with said grinding roll, a hopper supported on said brackets, means for adjusting the hopper with respect to the said two rolls, means for adjusting the feed roll with respect to the hopper and the grinding roll and means for adjusting the said bearing boxes.

7. In a roller mill of the character described the combination of bearing boxes, 125 brackets secured thereto, a grinding roll mounted in said bearing boxes, a feed roll mounted in said brackets in contact with said grinding roll, a hopper supported on said brackets, means for adjusting the hopper with 130

respect to the said two rolls, means for adjusting the feed roll with respect to the hopper and the grinding roll, means for adjusting the said bearing boxes and means for swinging said hopper away from the said rolls for the purposes set forth.
